CORE DRILLING APPARATUS

Frank C. Sturges, Pittsburgh, and Russell B. Strope, Rennerdale, Pa., assignors to Pennsylvania Drilling Company, Pittsburgh, Pa., a corporation of Pennsylvania

Application October 17, 1949, Serial No. 121,664

5 Claims. (Cl. 255—72)

1

This invention relates to core drilling apparatus and more particularly, it is concerned with structures combining a shot core drill with a core puller in a single unit together with novel arrangement for operating both the core drill and the core puller from a single drill rod.

The shot core drill is the standard piece of boring apparatus employed in the rock-drilling field for boring large diameter holes. The most common form of the shot core drill is the drill-rod type in which the bit is rotated by a hollow rod driven by gearing located on the surface. When the bit has penetrated to a depth equal to its height, the core must be removed from the drilling before further work can continue. Small cores up to about 20 inches in diameter are released by introducing small pieces of gravel into the wash water flowing to the rotating bit. The gravel becomes wedged between the bit and the core, breaking off the latter and holding it securely enough so that it can be raised to the surface with the bit.

In recent years, the scope of usage of the shot core drill has been expanded. Thus, this type of apparatus is now being employed in the drilling of mine shafts, ventilating shafts for mines, escape shafts, and the like. This raises the size of the cores to 36 inches in diameter or larger and the cores of this size must be removed by a different method from that employed with the smaller types of cores. Practice in the past has made use of two separate pieces of apparatus in this type of operation. First, the core is drilled with the standard type of shot core bit and after a core of sufficient depth has been cut, the drill barrel is lifted out of the hole by means of the hoist on the surface. After excess water is withdrawn by a baler or pump, the core is either broken off at its base by a man lowered into the shaft, by driving wedges along one side or by explosion of a small charge of dynamite after which the core is lifted out by means of a cable fastened to the top. A second method of removing the core makes use of a core puller which is generally cylindrical in size and which slips over the core. The core puller is provided with wedges or other gripping means which grasp the core and can be used to break it off and lift it to the surface.

A principal object of this invention is the provision of new core drilling devices which eliminate the necessity of employing separate core drills and core pullers. Further objects include,

(1) the provision of shot core drills provided with a built-in core lifting device;

(2) the provision of a new method for drilling

2

large-size cores and removing the cores from the drilling without requiring the insertion of separate core pulling apparatus or mechanism into the hole subsequent to withdrawal of the core drill;

(3) the provision of new mechanisms which make it possible to operate both a core drill and a core puller from a single drill rod.

Still further objects and the entire scope of applicability of the present invention will become apparent from the detailed description given hereinafter; it should be understood, however, that the detailed description and specific examples, while indicating preferred embodiments of the invention, are given by way of illustration only, since various changes and modifications within the spirit and scope of the invention will become apparent to those skilled in the art from this detailed description.

These objects are accomplished according to the present invention by the provision of a shot core drill having a core puller of the contractible, slotted type disposed coaxially within the barrel and means which causes the drill to operate freely of the core pulling section when the drill rod is rotated in one direction and actuates the core puller for gripping of the drilled core upon rotation of the drill rod in the opposite direction.

The new procedures and structures of this invention will become more apparent from the detailed description given hereinafter, with reference to the accompanying drawings, in which:

Figure 1 is a vertical cross section of the preferred form of the new drilling devices of this invention, showing the apparatus in position for drilling;

Figure 2 is a sectional side view of the apparatus shown in Figure 1, showing the relationship of parts of the device when it is in position to remove the core.

Referring in detail to the drawings, the core drill device 2 consists fundamentally of a core barrel 4, a core puller 6 and actuating means 8.

The core barrel 4 is provided at its lower end with a drill shoe 10, while a head plate 12 is fixed across the top end of the barrel forming a sludge chamber 14 at the top of the device. The drill shoe 10 is provided at the top with a wedge member or ring 16 which tapers from the inner side of the shoe back to the barrel. The shoe 10 also has slots 18 therein for cooperation with the shot used in drilling in well known fashion and is fastened to the barrel 4 by means of rivets 20.

The head plate 12 of the barrel 4 is divided into two sections consisting of a circular plate 22 fastened, such as by welding, to the barrel 4 and a key plate 24, fastened by bolts 26 to the plate 22. Fastened to the key plate 24 is an inside threaded tubular member 28.

An outside threaded tubular member 30 is threaded through the member 28 and connects with the core puller 6 through the support member 32 which is fastened to the upper end of the puller 6. The tubular member 30 is free to rotate relative to the puller 6 by being connected to the member 32 through the bearings 34 and 36 which are pressed upon either side of the member 32 by means of the nut 38 on the lower end 40 of the member 30. Nut 38 is held in position upon the tubular section 30 by means of the pin 42.

A key plate 44 is fastened upon the tubular member 30 above the bearing 34 and below the head plate 12. Keys 46 are carried by the plate 44 which work in cooperation with the keys 48 carried by the plate 24, as will be explained more fully below.

The core puller 6 has slots 50 in the lower end thereof and wedge dogs 52 which form contractible engaging members for breaking and lifting of a drilled core. There is also provided on the inside of the puller 6 a shot dispersing cone 54 held in position below the end 40 of the member 30 upon bolts 56.

A description of the apparatus is completed by reference to drill rod 58 having flanged end 60 which is bolted to the flanged end 62 of the member 30 by bolts 64.

The operation of the device is as follows: The drill rod 58 is rotated in one direction until movement of the threaded section 30 within the member 28 causes the core puller 6 to be lifted relative to the barrel 4 and keys 46 engage keys 48. As long as rotation in this direction of the drill rod 58 is continued, the core puller 6 will remain in the drawn-up position, as shown in Figure 1. With the apparatus so arranged, the device 2 is lowered into the hole and drilling commenced in normal fashion by rotation of the drill through the rod 58, while water and shot are supplied through the rod 58 and the tubular member 30 for distribution by the cone 54 to the drill shoe 10.

After the drill has been rotated in one direction and the drilling operation has been continued for a sufficient time to bring the top of the core 66 near to the cone 54, rotation of the drill in the drilling direction is stopped and rotation of the drill rod 58 is reversed. Friction between the walls of the hole 68 and the barrel 4 holds the barrel stationary, while the reversal of rotation of the rod 58 is commenced with. This causes the member 30 to be threaded down the member 28 causing a corresponding downward movement in the puller 6 relative to the barrel 4 and the wedge member 16. Continued rotation of the rod 58 in this fashion finally brings the dogs 52 into contact with the wedge ring 16 and forces them against the core 66. Sufficient force is readily applied through the rod 58 to cause the wedge dogs 52 to grasp firmly the core 66. When this happens, rotation of the rod 58 is discontinued and sufficient hoisting pull is applied to the rod 58 to break the core loose and then lift the device 2 out of the hole along with the core 66.

As stated before, the description above and the drawing relate to a preferred type of apparatus which may be modified to some extent, while, at the same time, utilizing the basic new concepts

of construction for drilling devices as provided by this invention. Thus, cone 54 can be omitted and various units, such as the wedge ring 16 and plate 24 can be formed as an integral part of their associated members 10 and 22 respectively, if this is desirable from the aspect of construction. Whatever minor modifications of this type are made, the new devices of this invention eliminate the need for using separate core pullers in shot core drilling operations. As a result, it is possible to materially increase the rate of drilling at a given location and also to eliminate the need for separate hoisting connections or the like, as is the case with separate core barrels and core pullers. By providing core drilling devices which can both drill and lift a core through the use of a single drill rod, further advances in the scope of usefulness of shot core drills can be realized.

The devices of this invention may be used for substantially all applications for which related units provided heretofore have been known to be useful, but these new units are distinguished from the prior structures in possessing additional capabilities. For example, it is often found impossible to break the core off at the bottom, and this has created a serious problem in the past. Now, however, the problem is generally overcome by the present apparatus since it is possible, if the core can not be broken at the base, to retract the core puller, and raise the puller and drill up a short distance and again apply the puller to the core. In a majority of the cases, this operation, or a repetition thereof, permits the core to be broken at a point which allows sufficient core to be removed to continue the drilling, e. g., at a bedding plane. All this, of course, is accomplished without need to remove drill or puller from the hole or similar troublesome operations. In addition, broken rock can be easily removed; eliminating another important trouble in this art.

We claim:

1. A shot core drilling device comprising in combination a core barrel carrying a drill shoe at its lower end, a wedge ring on the top of said shoe, a contractible, slotted, cylindrical core puller disposed coaxially within the core barrel having wedge dogs on the lower end, a head plate fixed across the upper end of said barrel, an inside threaded tubular member fastened in the center of the head plate coaxially with the barrel, an outside threaded tubular member threaded through said inside threaded member, a support member fixed to the top of the core puller and rotatably connected to said outside threaded member, a key plate fixed to said outside threaded member between said head plate and said support member and a key member fixed upon the bottom side of said head plate for operative engagement with said key plate.

2. A drilling device as claimed in claim 1 wherein said support member comprises a plate fixed across the top of said core puller.

3. A drilling device as claimed in claim 1 wherein said head plate is composed of two sections, the first section being a plate welded at its outside edge to the inside of the core barrel, said plate having a hole in the center thereof, the second part being a plate of smaller diameter than said first plate fastened by holding means over said hole in said first plate.

4. A drilling device as claimed in claim 1 wherein a shot dispersing cone is carried within said core puller below said support member with the apex of the cone substantially at the center

of the opening in said inside threaded tubular member.

5. A shot core drilling device comprising in combination a core barrel, a slotted drill shoe fixed to the lower end of the core barrel, a grooved wedge ring fixed upon the top edge of said drill shoe tapering in from the shoe edge to the inside of the core barrel, a contractible slotted, cylindrical core puller disposed coaxially within the core barrel, wedge dogs on the lower end of the core puller, a plate fixed to the upper end of the core barrel forming a sludge chamber in the top thereof, a central hole in said plate, a second plate smaller in diameter than said first plate covering said hole bolted to said first plate, a central hole in said second plate, an inside threaded tubular member fixed to said second plate above said second plate hole coaxially to the core barrel, an outside threaded tubular member threaded through said inside threaded member, a support plate fastened across the top of said core puller having a central hole therein to

15 receive the lower end of said inside threaded tubular member, a key plate fixed upon the inside threaded member between said support plate and said barrel plate, a bearing between said key plate and said support plate, a bearing beneath said support plate, a nut on the end of the inside threaded tubular member compressing said bearings against the sides of said support plate, and key members fixed to said second plate for operative engagement with corresponding key members carried by said key plate.
